[57] **ABSTRACT**

A lamp construction which includes a translucent lamp shade and a lamp socket fixture mounted therein. The lamp socket fixture is fixed to a cross brace and the cross brace is, in turn, fixed to the lamp shade. The cross brace is provided with end tabs which are received in slots provided in the lamp shade. According to one aspect of this invention, the cross brace is mounted in a vertical position in substantial alignment with the lamp socket fixture to minimize shadows on the lamp shade and to maximize cooling, convection air currents through the lamp shade to cool the lamp socket fixture.

LAMP CONSTRUCTION

BACKGROUND OF THE INVENTION

Lamp constructions have been proposed in which the lamp socket base is supported by a cross member having projecting ends which are connected to the lamp shade. In the case of a fabric lamp shade having a metal frame, the connection is generally between the cross brace and the frame itself. If the lamp shade is of a translucent plastic material, the cross brace is usually cemented to the lamp shade, or is received within a socket which is, in turn, cemented to the shade.

These prior art constructions involve time-consuming manual assembly operations which add to the cost of the lamp.

SUMMARY OF THE INVENTION

This invention provides an inexpensive lamp construction which may be easily assembled by the manufacturer, or by the purchaser. Thus, different diameter lamp shades may be nested together for shipping purposes and may be later easily assembled by the retailer or by the purchaser without the need for special tools or adhesives.

According to one aspect of this invention, the cross brace is a flat member which is fixed to the shade so that the plane of the cross brace is substantially vertical. This arrangement is particularly suitable for base-up bulb mountings in swagtype lamps. The vertical position of the cross brace minimizes shadows at the top of the lamp and maximizes convection currents through the assembly to cool the lamp fixture socket. This is particularly important in base-up installations, since in such installations the socket temperature of the bulb is about 160° F. for a 200-watt A-25 lamp. To further dissipate heat, the cross brace may be metal, such as aluminum, so that it acts as a heat sink to absorb heat from the socket and transfer the heat to the convection currents. If the lamp socket fixture includes an SCR dimmer control, such high temperatures, unless dissipated, may damage the SCR dimmer control.

According to a further aspect of this invention, the cross brace may be mounted in a horizontal plane in lamp constructions having a base-down bulb mounting.

BRIEF DESCRIPTION OF THE DRAWINGS

FIG. 1 is an elevational view of a swag lamp according to one aspect of this invention.

FIG. 2 is an enlarged cross sectional view, the plane of the section being indicated by the line 2-2 in FIG. 1.

FIG. 3 is a fragmentary plan view of the connection between the cross brace and the lamp fixture stem, with certain elements omitted for clarity.

FIG. 4 is an enlarged, fragmentary, perspective view of the cross brace for the lamp illustrated in FIG. 1.

FIG. 5 is an elevational view of a table lamp according to a further aspect of this invention.

FIG. 6 is a cross sectional view, the plane of the section being indicated by the line 6-6 in FIG. 5.

FIG. 7 is a cross sectional view, the plane of the section being indicated by the line 7-7 in FIG. 6.

DETAILED DESCRIPTION OF THE DRAWINGS

Referring now to the drawings, and particularly to FIGS. 1 through 3, a swag lamp according to one aspect of this invention is illustrated. The swag lamp includes a shade 10. The shade 10 is cylindrical and may be fabricated from a suitable translucent, light-diffusing material. A particularly suitable material for the lamp shade 10 is a fiber-reinforced plastic cylinder which may be produced in accordance with the teachings of Randolph Reissue Pat. No. Re 25,214. Articles produced according to the above-noted Randolph patent which are not suitable for pressure vessel applications due to defects in their pressure-retaining characteristics and which would otherwise be scrapped may be fabricated into lamp shades by cutting cylindrical sections from the sidewall of the rejected tanks. Of course, it should be appreciated that other translucent materials may be employed without departing from this invention.

The lamp shade 10 may be provided with scalloped portions 11 and 12 at the top and bottom of the shade for aesthetic purposes. The lamp shade 10 is provided with diametrically opposed slots 13, 14, 15, and 16. The slots 13 and 15 on the one hand and the slots 14 and 16 on the other hand are aligned with the axis of the shade 10. A cross brace 17 is provided within the shade 10. The cross brace 17 is planar and may be fabricated from a suitable metal stamping for heat dissipation, or may be fabricated from plastic or a fiber-reinforced plastic if heat dissipation is not a problem. The cross brace 17 is provided with end tabs 18, 19, 20, and 21, which are respectively received in the slots 13, 14, 15, and 16. To mount the cross brace 17 within the shade 10, pressure may be applied to diametrically opposed portions 22 and 23 of the lamp shade 10 to expand the portions of the lamp shade having the notches 13-16 therein. When the pressure is relieved, the tabs 18-21 will enter the slots 13-16 and will therefore firmly attach the cross brace 17 to the shade 10.

The cross brace 17 is provided with a T-shaped aperture 24 at its central portion. Received by the aperture 24 is a threaded stem portion 25 of a lamp socket fixture 26. The portion 25 is engaged by a nut 27, and a metal washer 27a and a rubber washer 27b are provided beneath the nut 27. The nut 27, together with its washers 27a and 27b, firmly clamps the fixture 26 in place. To prevent the fixture 26 from rotating, opposite sides of the stem portion 25 are provided with grooves 28 which receive projections 29 of the aperture 24.

A switch handle 30 projects radially outwardly from the fixture 26 and through an aperture 31 in the shade 10. The fixture 26 may be an off-on type fixture which is operated by the handle 30, or may be an SCR dimmer control fixture which is operated by the handle 30.

The lamp shade 10 is supported as a swag lamp by a chain 32 which is attached at one end to an aperture 33 in the cross brace 17.

The slots 13-16 and the projecting ends of the tabs 18-21 are covered by a diametrically opposed pair of a plurality of longitudinally extending decorative strips 34 which are provided on the outside surface of the lamp shade 10. The strips 34 may be metalized plastic having a pressure-sensitive adhesive coating thereon for application to the lamp shade 10.

Referring now to FIGS. 4 through 6 of the drawings, a lamp 40 according to a further aspect of this invention is illustrated. The lamp 40 includes a cylindrical shade 41 which may be fabricated from a translucent material similar to the material employed in fabricating the lamp shade 10. The lamp 40 is a table lamp having supporting legs 42 which are provided by removing portions from one end of the shade 41. Of course, it should be appreciated that the supporting end of the lamp 40 may be entirely planar, but by providing the legs 42 air circulation through the spaces between the legs dissipates heat from the lamp bulb.

A cross brace 43 is provided within the shade 41. The cross brace 43 comprises a flat sheet which may be stamped from metal, or may be formed from a suitable plastic or a suitable fiber-reinforced plastic. The cross brace 43 may be mounted in a position which is vertical (similar to the mounting arrangement of the cross brace 17), or may be mounted in the illustrated horizontal position, since the illustrated base-down bulb mounting would not generate as much heat in the lamp socket fixture as would a base-up bulb mounting arrangement.

The cross brace 43 is provided with projecting end tabs 44, 45, 46, and 47. The projecting end tabs 44-47 are respectively received in slots 48, 49, 50, and 51. The tabs 44-47 may be inserted into the slots 48-51 by compressing diametrically opposed portions 52 and 53 of the shade 41 to outwardly expand the portions of the shade containing the slots 48-51. While the latter-mentioned portions are expanded outwardly, the cross brace 43 may be positioned within the shade 41 and the pressure applied to the diametrically opposed portions 52 and 53 may be released to insert the tabs within the slots.

The cross brace 43 supports a lamp socket fixture 54. The lamp socket fixture 54 has a threaded stem 55 which extends through an aperture 56 in the cross brace 43 and a nut 57 is threaded onto the projecting end of the stem 55. A control knob 58 extends from the fixture 54 and through an aperture 59 in the shade 41. A cord 60 from the fixture 54 may extend through an aperture 61 in one of the legs 42, or may extend through an opening provided by the legs 42.

A decorative trim strip 63 is applied to the shade 41 to conceal the tabs 44-47 and the slots 48-51.

The invention is not restricted to the slavish imitation of each and every detail set forth above. Obviously, devices may be provided which change, eliminate, or add certain specific details without departing from the scope of the invention.

What is claimed is:

1. A lamp construction comprising a shade, a substantially planar cross brace extending radially inwardly from said shade and supporting a lamp fixture thereon, said cross brace having tab means projecting outwardly from its ends, said shade having slot means therethrough to provide apertures in said shade, said tab means being received in said apertures so that said cross brace is rigidly connected to said shade, said cross brace being mounted within said shade so that the plane of said cross brace is substantially vertical, and said lamp fixture being fixed to and extending downwardly from said cross brace,

2. A lamp construction comprising a shade, a substantially planar cross brace mounted within and extending radially inwardly from said shade so that the plane of said cross brace is substantially vertical, said cross brace having tab means projecting outwardly from its ends, said shade having slot means therethrough to provide apertures in said shade, said tab means being received in said apertures so that said cross brace is rigidly connected to said shade, a T-shaped aperture in a midportion of said cross brace, said T-shaped aperture being formed by a first opening which forms a vertical leg that opens at the bottom edge of said cross brace and being formed by a second opening which forms a horizontal leg extending across the top of said first opening, a lamp fixture having a threaded end stem supported by said cross brace, said threaded stem extending along the vertical extent of said vertical leg, groove means in diametrically opposed portions of said stem, portions of said vertical leg extending into said groove means, and a nut threaded onto said stem and extending along the horizontal extent of said horizontal leg.

3. A lamp construction according to claim 2, wherein suspending means is attached to said cross brace.

UNITED STATES PATENT OFFICE
CERTIFICATE OF CORRECTION

Patent No. 3,683,175 Dated August 8, 1972

Inventor(s) ARTHUR J. WILTSHERE

It is certified that error appears in the above-identified patent
and that said Letters Patent are hereby corrected as shown below:

Column 2, line 11, "25,214" should be --25,241--.

Signed and sealed this 8th day of May 1973.
